Patent No. 2,615,963

RESETTABLE CIRCUIT BREAKER

Ben Millen, Cleveland, Ohio

Application January 5, 1951, Serial No. 204,523

4 Claims. (Cl. 175—294)

1

This invention relates to a circuit breaker of the resettable type employing a temperature responsive bimetal element as the means for breaking the circuit.

It is an object of this invention to provide a circuit breaker in the form of a plug-in fuse which is of very simple construction and which is, therefore, capable of being manufactured very economically.

Another object of the invention resides in the provision of a circuit breaker having a push button which is depressible to reset the breaker after the thermostatic bimetal element has responded to an overload to break the circuit.

A further object of the invention resides in the provision of a circuit breaker having a fusible element connected in series with a thermostatic bimetal element which serves as a positive circuit breaker when the circuit is overloaded to a predetermined extent regardless of the condition of the bimetal element.

A still further object of the invention is to provide a circuit breaker in the form of a plug-in fuse having a pair of contact points which are movable to open and close the circuit and which are designed to give relatively long service.

In the drawings:

Figure 1 is a vertical sectional view through the fuse.

Figure 2 is a fragmentary perspective view of the fuse body.

Figure 3 is a top view of the fuse.

Figure 4 is a detailed view showing a modified construction of contact points for the circuit breaker.

Referring to the drawings, it will be seen that the fuse of this invention resembles to a great extent a fuse of conventional design in that it includes a body member 10 of insulating material which may be formed as a lower member 12 and a cap member 14, the sides of the lower member 12 having threads 16 formed thereon to receive a shell member 18 which is correspondingly threaded. Bottom 12 and cap member 14 may be secured together by any suitable means as at 20. Bottom member 12 is fashioned with a central chamber 22, at the lower end of which there is a recess 24.

A bimetallic arm 26 is mounted in chamber 22 with its lower end seated at the base of recess 24. Arm 26 is secured to bottom 12 by a rivet 27 which extends through an aperture 30 in member 12.

A bushing 32 has a reduced portion 34 which separates and thereby insulates the lower end of arm 26 from rivet 27. Rivet 27 is, however,

connected to arm 26 through a fusible element 36 which has one end disposed between the head 38 of rivet 27 and bushing 32 and its other end extending between the lower face of bushing 32 and the lower end of arm 26. It will be observed that rivet 27 clamps bushing 32, element 36, and the lower end of arm 26 to the base portion of member 12.

Bottom member 12 is provided at one side thereof with a slot 40 extending through the threaded portion 16 thereof. The slot 40 is provided for retaining a spring arm 42 on member 12. Arm 42 has a corrugated end portion 44 which seats in slot 40 and interfits with the threaded portion 16. The thickness of the corrugated end portion 44 of arm 42 is slightly less than the depth of slot 40 so that when the arm is seated in slot 40 and shell 18 arranged over member 12, a narrow passage is provided between a corrugated portion 44 and shell 18 which may be filled with solder through an inlet 46 at the upper end of slot 40 so as to thereby solder arm 42 to shell 18 along their adjacent faces as at 47.

The free end of arm 42 extends through an opening 48 in the wall of member 12 and into chamber 22. At its upper end arm 26 is shaped to provide a downwardly hooked portion 52 which in its normal position is arranged to engage the free end of arm 42 and hold it in a downwardly flexed position. The extreme free end portions of arms 26 and 42 are embedded within contact points 54 and 56, respectively. These contact points are formed of a material such as a nickel-silver alloy which is relatively unaffected by the arcing which occurs when the points open and close the circuit.

On its upper face, cap 14 is provided with a recess 56 at the center of which there is a hole 58 extending from recess 56 into chamber 22. Within hole 58 there is slidably mounted a button member 60. The length of button 60 is somewhat greater than the thickness of cap 14 and the button is arranged such that its lower end 62 engages the upper side of arm 42 at a point spaced inwardly from contact point 56. At its upper end, button 60 is provided with a head portion 64 which, when the button is in the depressed position, seats in recess 56.

When arm 42 is engaged by the bimetallic arm 26, head 64 of button 60 is substantially flush with the top surface of cap 14. However, when the circuit becomes overloaded to an extent such that arm 26 is heated and flexed so as to disengage hook 52 from arm 42, arm 42 springs upwardly and shifts button 60 outwardly so that

its head 64 projects above the upper face of cap 14 as is shown in broken lines in Figure 1. When it is desired to reset the fuse after the circuit is broken, button 60 is simply depressed so that the lower end 62 thereof engages arm 42 and flexes it downwardly. If the resetting operation is performed after arm 26 has cooled sufficiently to assume its normal upright position, shown in solid lines, contact 56 engages contact 54 and flexes arm 26 outwardly to the dotted line position shown in Figure 1. When contact 56 passes beneath the lower end of contact 54, arm 26 springs back to its normal position where contact 56 is engaged beneath contact 54. Thereafter, if the circuit should become overloaded for some reason, arm 26 will become heated in proportion to the amount of overload in the circuit and will begin to flex outwardly out of engagement with arm 42. When the overloading conditions exceed the rating of the fuse, arm 26 will be flexed to a position wherein contact 54 disengages contact 56 and thus permits arm 42 to spring upwardly and push button 60 outwardly to the projected position.

It will be noted that contacts 54 and 56 are shaped such as to prevent direct contact between arms 26 and 42, both when arm 42 is pushed downwardly into engagement with arm 26 and when arm 26 becomes heated and flexed outwardly to disengage arm 42. Arm 26 will, of course, be designed to flex a desired amount in accordance with the desired rating of the fuse. If the fuse is rated at 30 amperes, the arm 26 will disengage arm 42 when the current in the circuit exceeds 30 amperes. Fusible element 36 is provided as a safety feature and is designed to melt and break the circuit if for some reason arm 26 fails to function. Accordingly, element 36 is designed to burn out at a current value slightly above the rating of the fuse. If the fuse is rated at 30 amperes, element 36 is designed to burn out at about 33 to 35 amperes.

In Figure 4 I have shown a modified construction for the contact points at the free ends of arms 26 and 42. In this arrangement the contact point 70 on arm 42 and the contact point 72 on the arm 26 are formed as two integrally connected half portions, the portion 74 being formed of a conducting material such as a nickel-silver alloy and the portion 76 being formed of a non-conducting material such as Bakelite or cold-molded rubber. Contact point 70 is fashioned with the conducting portion 74 forming the top half and with the non-conducting portion 76 forming the bottom half of the point. Contact 72 is fashioned with the conducting portion 74 forming the bottom half and the non-conducting portion 76 forming the top half of the contact.

It will be noticed that with the arrangement illustrated in Figure 4 very little arcing occurs either when the circuit is broken or reset. When the circuit becomes overloaded to an extent such as to cause bimetallic arm 26 to flex to the position shown in broken lines, contact point 70 springs upwardly out of engagement with contact point 72. As soon as electrical contact between these points is broken, it will be noted that the non-conducting portions 76 of the contacts wipe past one another rather than the conducting portions 74. This action tends to substantially reduce the tendency for arcing between the contacts 70 and 72.

When the contacts are in the separated condition illustrated in broken lines and it is desired to reset the fuse, it will be noted that, as the

contact 70 is depressed into engagement with contact 72, the most proximate portions of the two contacts are the insulating portions 76. Therefore, as the contacts approach one another, there is no tendency for arcing. As the contact 70 moves downwardly into engagement with contact 72, the non-conducting portion 76 of contact 70 engages the non-conducting portion 76 of contact 72 and the circuit is established only when these portions wipe past one another so that the conducting portion 74 of contact 70 contacts the conducting portion 74 of contact 72.

It will thus be seen that I have provided a very simply constructed circuit breaker for a plug-in fuse socket. The provision of the projectable button 60 enables the user to determine at a glance which of several circuits in a fuse box has been opened through the operation of the circuit breaker. Moreover, the resetting operation is performed safely and quickly by merely depressing button 60.

It will be noted that all of the electrical conducting members of the circuit breaker are inaccessible when the fuse is disposed within a fuse socket and there is no danger, therefore, of the user receiving a shock when he attempts to reset the fuse. This application is a continuation-in-part of my earlier application Serial No. 107,313, filed July 23, 1949, and now abandoned.

I claim:

1. A resettable circuit breaker comprising a shell adapted to be inserted into a conventional plug-in fuse socket, said shell forming a contact member, a body of insulation material circumferentially enclosed by said shell, said body having a substantially enclosed chamber therein, rivet means at the lower end of said body having a shank portion extending upwardly through the bottom wall of said body and projecting into said chamber, said shank portion having a head at the inner end thereof, a disc of insulating material on said shank portion disposed between said head and the bottom wall of said body, a bimetallic arm extending upwardly in said chamber and having its lower end bent laterally to project beneath said disc of insulation material, a fusible member having one end thereof disposed between the lower face of said head and the upper face of said disc and having its other end projecting beneath the lower face of said disc, said head being arranged to clamp the lower end of said bimetallic arm and said other end of said fusible element in contacting relation between the lower face of said disc and the bottom wall of said body, said disc having a portion on the lower side thereof effectively insulating said clamped ends from the shank portion of said rivet means, a spring arm connected with said shell and projecting transversely through said chamber, said bimetallic arm having a free end thereof lying in the path of movement of the free end of said spring arm such that the free end of said spring arm is engageable with said bimetallic arm when said spring arm is flexed downwardly, and a push button slidably arranged in the top wall of said body and engageable with said spring arm for flexing said spring arm downwardly into engagement with the free end of said bimetallic arm.

2. A resettable circuit breaker comprising a shell adapted to be inserted into a conventional plug-in fuse socket, said shell forming a contact member, a body of insulation material circumferentially enclosed by said shell, said body having a substantially enclosed chamber therein, a

contact member at the lower end of said body extending upwardly into said chamber, a bimetallic arm in said chamber connected at one end to one of said contact members, a resilient arm in said chamber connected to the other of said contact members, said body having an aperture at the upper end thereof, a pin slideable in said aperture and having its inner end projecting into said chamber, said spring arm being biased to engage the inner end of said pin at a point spaced from the free end of said spring arm and shift said pin in said apertures so that the outer end of the pin projects above the outer surface portions of said body surrounding said aperture, said bimetallic arm in its normal position having a portion lying in the path of movement of the free end of said spring arm, said pin in the outwardly projected position being arranged to be depressed to interengage said spring and bimetallic arms to hold said spring arm in a flexed position and thereby permit said pin to remain in a depressed position, said spring and bimetallic arms having the free ends thereof imbedded in individual contact members, said last mentioned contact members comprising an electrical conducting portion and a non-conducting portion, said non-conducting portion comprising the upper portion of said contact member at the free end of said bimetallic arm and the lower portion of the contact member at the free end of said spring arm and said conducting portion comprising the lower portion of the contact member at the free end of said bimetallic arm and the upper portion of the contact member on said spring arm.

3. A resettable circuit breaker comprising a shell adapted to be inserted into a conventional plug-in fuse socket, said shell forming a contact member, a body of insulation material circumferentially enclosed by said shell, said body having a substantially enclosed chamber therein, rivet means at the lower end of said body having a shank portion extending upwardly through the bottom wall of said body and projecting into said chamber, said shank portion having a head at the inner end thereof, a disc of insulating material on said shank portion disposed between said head and the bottom wall of said body, a bimetallic arm extending upwardly in said chamber and having its lower end bent laterally to project beneath said disc of insulation material, a fusible member having one end thereof disposed between the lower face of said head and the upper face of said disc and having its other end projecting beneath the lower face of said disc, said head being arranged to clamp the lower end of said bimetallic arm and said other end of said fusible member in contacting relation between the lower face of said disc and the bottom wall of said body, said clamped ends being spaced out of contact with the shank portion of said rivet means, a spring arm connected with said

shell and projecting transversely through said chamber, said bimetallic arm having a free end thereof lying in the path of movement of the free end of said spring arm such that the free end of said spring arm is engageable with said bimetallic arm when said spring arm is flexed downwardly, and means extending through the wall of said body and engageable with said spring arm for flexing said spring arm into engagement with the free end of said bimetallic arm.

4. A resettable circuit breaker comprising a shell adapted to be inserted into a conventional plug-in fuse socket, said shell forming a contact member, a body of insulation material circumferentially enclosed by said shell, said body having a substantially enclosed chamber therein, rivet means at the lower end of said body having a shank portion extending upwardly through the bottom wall of said body and projecting into said chamber, said shank portion having a head at the inner end thereof, a disc of insulating material on said shank portion disposed between said head and the bottom wall of said body, a bimetallic arm extending upwardly in said chamber and having its lower end bent laterally to project beneath said disc of insulation material, a fusible element having one end thereof contacting said head of said rivet means and having its other end projecting beneath the lower face of said disc, said rivet means being arranged to clamp the lower end of said bimetallic arm and said other end of said fusible element in contacting relation between the lower face of the disc and the bottom wall of said body, the shank of said rivet means extending through said clamped ends but spaced out of contact therefrom, a spring arm connected with said shell and projecting transversely through said chamber, said bimetallic arm having a free end thereof lying in the path of movement of the free end of said spring arm such that the free end of said spring arm is engageable with said bimetallic arm when said spring arm is flexed downwardly, and a reset mechanism comprising a member extending through a wall of said body and engageable with said spring arm for flexing the spring arm into engagement with the free end of said bimetallic arm.
